ADJUSTABLE LABELING DEVICE

Howard B. Tuthill and Harry F. Caldwell, Grand
Rapids, Mich., assignors to Oliver Machinery
Company, Grand Rapids, Mich., a limited part-
nership of Michigan

Application January 13, 1944, Serial No. 518,032

3 Claims. (Cl. 216—29)

This invention relates to labeling, and is primarily concerned with a simple, practical construction by means of which labels may be applied to wrapping paper or the like at different positions in the length of the paper which is afterward used for wrapping articles.

In practice a continuous length of the wrapping paper is drawn over a horizontal under support, labels attached to the paper at periodic intervals in its passage and the paper then cut transversely to provide sheets at a side of each of which a label is secured. The sheets of the proper length for the articles which they are to wrap carry a label so that when the article is wrapped, the label having been previously applied to the paper used appears on the wrapped article.

The paper prepared for wrapping the articles, with different sizes of articles, will have sheets cut therefrom of different lengths, therefore it is necessary that the application of the label and its place of application on each of the several sheets shall be controlled in order that the label shall properly appear on the wrapped article after it is wrapped. There are other circumstances in which a change in position of the label attaching mechanism with respect to the paper is desirable, and the present invention is directed to the adjustment and location of the label applying and attaching mechanism with reference to the paper to which the labels are applied and attached in order to control and properly attach the labels at desired positions in the length of the paper and with one label on each of the sheets cut therefrom.

An understanding of the invention and embodiment thereof which has been produced will be understood from the following description, taken in connection with the accompanying drawings, in which,

Fig. 1 is an elevation partly in section showing the adjustable label device of our invention, the section being taken upon the plane of line 1—1 of Fig. 2.

Fig. 2 is a fragmentary vertical section substantially on the plane of line 2—2 of Fig. 1.

Fig. 3 is a fragmentary side elevation with parts broken away illustrating the method of securing the label attaching device at any position to which adjusted, and,

Fig. 4 is a vertical section of a detail of the structure substantially on the plane of line 4—4 of Fig. 2.

Like reference characters refer to like parts in the different figures of the drawings.

In the construction of the machine shown, an under support is provided having vertical spaced apart sides 1 (suitably connected together by cross members, some of which will be later described, and between which the wrapping paper in a roll indicated at 2 is carried on a horizontal inner core. Said paper 3 is unwound from the roll 2 and upwardly over a change direction idle roller 4 at one end of the machine and thence horizontally over the upper side of the support. It is drawn between upper and lower rollers 4 and 5, the detail of driving which is not of importance in the present invention. However the driving roller drives continuously for a period of time and then is stopped for a short interval, during which time the label is applied to the paper, the driving of the roller thereafter continuing and with periodic stops in said driving for the successive attachment of the labels to the paper. After the paper with a label attached has passed through the rollers 4 and 5 it comes to and over a receptacle 6 located between the sides 1 and below their upper edges, and is severed at the rear edge of a cross bar 7 between the sides 1 by the downward passage of a cutting knife 8 carried by arms 9 which may be pivotally mounted at their opposite ends (not shown) and operated periodically to cut the paper across, thereby depositing successive sheets one after another in the receptacle 6. Each of the sheets when thus severed will have a label affixed to its upper side as hereinafter outlined.

At the upper edge of each of the sides 1 and at the inner sides thereof longitudinal bars 10 (Fig. 2) are permanently secured which serve as supporting tracks for the label attaching machine. Between the sides 1 a channel bar 11 having a plate 12 secured to the upper side of the web of the channel bar is located longitudinally of the machine and is supported and held in a horizontal position at its rear end by cross bar 13 extending between the tracks 10 and secured thereto, and at its outer end by a diagonal brace bar 14 connected at its upper end to the channel 11 and at its lower end to a cross frame bar 15 between the sides 1.

The label attaching device is disposed over the upper side of the channel 11 and the plate 12 secured at the upper side of the channel. It includes a spool 16 on which a continuous length of labels, indicated at L, is wound, said strip being carried over idle change direction rollers 17 (Fig. 1) and thence around a roller 18 which has pairs of pins projecting therefrom for engagement in the side notches shown in the label

strip L, this properly locating the labels and, the roller 18 being driven, for drawing the strip of labels from the spool 16 on which the strip is wound. The label machine also includes a severing knife 19 for successively cutting from the lower end of the label strip end labels, indicated at L1, and a heated sealing member 20 which is brought down upon the upper side of an end label L1 after it has been severed from the label strip and deposited on the paper. The under side of the end label L1 which has been thus cut from the label strip carries a thermoplastic material which under the effect of the heat supplied softens and adheres to the paper. Any further detail of the construction and operation of the labeling machine is not required in the disclosure of the present invention. Reference may be made to Patent No. 2,326,436 granted August 10, 1943, for Label attaching machine upon the application of Harry F. Caldwell for details of construction and of the operation of the immediate label attaching mechanism.

The various parts of the label mechanism mentioned are supported on a support 21 which at one side has connected therewith a housing 22 (Fig. 2), the outer side 23 of which at its lower edge is formed with a shoe 24 which engages with and rests upon one of the side tracks 10. A shaft 25 from the label mechanism extends to and over the opposite track 10 and at its end carries a shoe 26 to move thereover. The labels L1 severed from the label strip are deposited on the paper 3 directly over the upper plate 12 carried by the channel member 11, said plate 12 and channel member forming a relatively narrow table against which the paper is pressed when the sealing of the label to the paper is done. It will be evident that the labeling device supported by and mounted upon the tracks 10 may be moved to different positions on said tracks by merely sliding the shoes 24 and 26 thereover. When a desired position is reached the labeling device is releasably held in such position by a manually operable screw 27 which passes downwardly through the housing at 22 and through a clip 28 (Fig. 3) which extends to one side underneath the track 10 with which the shoe 24 engages.

The driving of the label mechanism is by a shaft 29 mounted at one end in a bearing on a side 23 of the housing, which shaft carries a sprocket around which an endless chain 30 passes. The chain 30 also passes around a driving sprocket on a short shaft 31 which is mounted in a bearing at the lower end of a bar 32 which has a sleeve at its upper end through which the shaft 29 passes; therefore the bar 32 is suspended from the shaft 29 and has a pivotal connection thereto. Shaft 31 carries a second sprocket wheel 33 around which a driving chain 34 passes for driving the shaft 31, and thence through the chain 30, driving the shaft 29.

The shaft 31 extends at one end toward the adjacent side 1 of the under support and is in engagement with the inwardly extending leg of a length of angle bar 35 secured by welding or otherwise permanently at the inner side of said side 1. Said end portion of the shaft 31 is drawn against said leg of the angle by the pull of the driving chain 34. In the movement of the labeling device to different positions in the length of the tracks 10, said movement being a straight line movement in a horizontal direction, the shaft 31 will be moved vertically along the leg of the

angle 35 but will always be maintained in contact therewith.

The described construction is practical and simple for the attainment of the results and functions desired. By changing the position of the labeling device on the tracks 10 the relative position of the labels deposited on the paper is changed and desired location for the attachment of the labels to the paper within the limits of adjustable movement of the labeling device may be had. With this construction there is no carrying of the paper with an attached label around any roller or the like which when it occurs, as previously done, may at times cause a disengagement of the label from the paper; but the paper after the label is attached is carried in the same plane and with no bending of the paper and attached label around any roller or otherwise in changing direction of movement.

It is of course to be understood that this invention is not restricted to securing of labels to the paper at spaced intervals and thereafter the cutting of the paper transversely to provide wrapping sheets with labels attached. The paper with the labels successively attached at the desired intervals in the length may be carried directly into a wrapping machine to wrap articles, the paper used to wrap each article being severed in the wrapping machine. The invention accordingly is to be considered comprehensive of all forms of structure and the uses thereof comprehended in the appended claims defining the invention.

We claim:

1. In a construction of the class described, a support over which paper is adapted to be drawn, a labeling mechanism thereover including means for feeding labels to said paper and successively severing end labels from a strip of labels to deposit said end labels on the paper at spaced distances in the length thereof, and further including means for securing the severed labels to the paper, tracks for supporting the labeling mechanism on which said mechanism may be adjusted to different positions over the paper and said support therefor, and means for driving said labeling mechanism located underneath said support.

2. A construction containing the elements in combination defined in claim 1, said means including a driven shaft connected with the labeling mechanism, a bar suspended from said shaft, a short shaft mounted at the lower end of said bar, means for driving the first mentioned shaft from the short shaft, said shaft having a projecting end portion and a vertical member having a vertical face against which the projecting end of the shaft is held by the driving means therefor, said projecting end of the portion of the short shaft being adapted to move to different vertical positions against the face of said vertical member on adjustment of the labeling mechanism to different positions.

3. A construction of the class described comprising a frame, means for feeding a continuous length of paper relative to said frame, means for periodically cutting said paper into predetermined lengths, a labeling machine including means for periodically attaching labels to said paper, said labeling machine being mounted on said frame for adjustment longitudinally of said paper and relative to said cutting means.

HOWARD B. TUTHILL.
HARRY F. CALDWELL.
